UNITED STATES PATENT OFFICE.

JAMES B. CRIST, OF EVANSVILLE, INDIANA.

GRAIN-SEPARATOR.

Specification of Letters Patent No. 23,903, dated May 10, 1859.

To all whom it may concern:

Be it known that I, J. B. CRIST, of Evansville, in the county of Vanderburg and State of Indiana, have invented a new and Improved Grain-Separator; and I do hereby declare that the following is a full, clear, and exact description of the same, reference being had to the annexed drawings, making a part of this specification, in which—

10 Figure 1, is a longitudinal vertical and central section of my invention. Fig. 2, a transverse vertical section of same taken in the line α , α , Fig. 1.

15 Similar letters of reference indicate corresponding parts in the two figures.

This invention consists in a peculiar arrangement of a fan, blast spout, riddle and screen, and discharge passages, as herein-after fully shown and described, whereby 20 the desired work, to wit, the cleaning of grain or the separating it from all foreign substances is performed in a very expeditious and perfect manner and by a very economical device.

25 To enable those skilled in the art to fully understand and construct my invention I will proceed to describe it.

A, represents the case or box which encloses the working parts of the machine. B, 30 represents a fan box placed in the upper part of the case or box, and B', is the fan placed therein, the shaft D, of which passes through the bottom of a projecting upper part E, of the case and is stepped at a, the 35 shaft extending down by the side of the lower part F, of the case or box, as shown plainly in Fig. 1. In the upper part of the fan box B, an opening b, is made which forms a communication between the fan box 40 and the interior of the case A.

At one side of the case or box A, there is a blast passage G, which communicates with the upper part E, of the case A, said blast passage having a hopper H, attached to one 45 side of it. The lower part F of the case or box communicates with the upper part E, by a passage c, and within the part F, an inclined riddle I, is placed, said riddle being driven or having a proper shake motion 50 communicated to it by an eccentric J, on shaft D. Below the riddle I, an inclined screen K, is placed, the screw being inclined more than the riddle and in an opposite position, as shown clearly in Fig. 1. To the 55 under side of the screen K, a chute L, is attached, to carry off cockle and other fine and

heavy impurities. The screen K, is also operated from shaft D, by an eccentric M.

The lower or depressed end of the riddle I, is directly over a vertical discharge passage d, in the part E, of the case, and a discharge passage e, is directly underneath the chute L. The lower end of the screen K, is opposite an opening f, in the lower part of the blast passage G, and there is an opening g, in the passage G, which conducts the grain on the riddle I, the blast passage G, being somewhat inclined or bent to effect such result. At the end of the projecting portion of the upper part E, of the case A, 70 there is a discharge passage N, in which a pendent valve h, is placed, the lower end of said valve abutting against the lower end of an inclined side i, of the discharge passage N, as shown clearly in Fig. 2. 75

The operation is as follows:—Motion is given the shaft D, in any proper manner and a blast of air is generated in the passage G, and also through the lower part F, of the case A. The grain to be cleaned 80 passes through or across the passage G, on the riddle I, through the opening g, and is subjected to a blast as it crosses said passage. The coarse foreign substances fall off the depressed end of the riddle I, into the 85 passage d, and are discharged from the case at the lower end of said passage, the grain passing through the riddle I, and falling on the screen K, and passing therefrom through the opening f, into the lower part of the 90 passage G, where it is subjected to a second blast as it leaves said passage. The cockle or fine heavy substances pass through the screen K, into the chute L, and are discharged through e. The screen and riddle 95 are actuated by the eccentrics, J, M, and all fine dust and light impurities are drawn up by the blast into the upper part E, of the case or box, and into the fan box B, and discharged through B'', which is the outlet of 100 the fan box B. Impurities and light grain which are rather too heavy to be actuated or governed entirely by the blast, will by their inertia, which is due to their weight, be carried over and beyond the fan box, and 105 into the spout N, the discharge from which is regulated by the valve h, which valve allows the contents of N, to escape without permitting air to pass up said spout. The black arrows show the direction of the 110 blast.

I am aware that blast passages have been

used in connection with fans and screens, and arranged in various ways, and I do not claim broadly and separately any of the parts herein shown and described; but,

Having thus described my invention, what I do claim as new and desire to secure by Letters Patent, is—

The arrangement of the blast passage G, fan B', screen I, and riddle K, with chute L,

attached, placed within the case or box A, 10 and in relation with the spouts or discharge passages d, e, f, N, to operate as and for the purpose set forth.

JAMES B. CRIST.
